OTHER PUBLICATIONS

Notice of Allowance dated Apr. 27, 2018, corresponding to Design U.S. Appl. No. 29/591,712.

Non-Final Office Action dated May 31, 2018, corresponding to U.S. Appl. No. 29/591,727.

Primary Examiner — Mimosa De

(74) Attorney, Agent, or Firm — Hogan Lovells US LLP

(57) **CLAIM**

The ornamental design for a vehicle seat, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view thereof;

FIG. 2 is a left side perspective view thereof;

FIG. 3 is a right side perspective view thereof;

FIG. 4 is a top view thereof; and,

FIG. 5 is a perspective view thereof.

1 Claim, 5 Drawing Sheets
(4 of 5 Drawing Sheet(s) Filed in Color)
